Henry G. Guyon

UNITED STATES PATENT OFFICE.

HENRY G. GUYON, OF BROOKLYN, NEW YORK, ASSIGNOR TO JAMES EDSALL, OF SING SING, NEW YORK.

IMPROVED SELF-RELIEVING HOOK FOR BOATS' TACKLE.

Specification forming part of Letters Patent No. 41,339, dated January 19, 1864.

To all whom it may concern:

Be it known that I, HENRY G. GUYON, of the city of Brooklyn, in the county of Kings and State of New York, have invented a new and Improved Self-Relieving Device for Boat-Tackle; and I do hereby declare that the following is a full, clear, and exact description of the same, reference being had to the accompanying drawings, forming part of this specification.

Figure 1 is a front view of the device. Fig. 2 is a vertical section of the same at right angles to Fig. 1. Fig. 3 is a side view showing the application of my device to boat-tackle.

Similar letters of reference indicate corresponding parts in the several figures.

This invention consists in a divided or slotted hook of peculiar construction to be attached to the boat, and a link of peculiar construction to be attached to the tackle, whereby the tackle is made to detach itself when the boat, in being lowered from a vessel in motion, comes to a bearing in the water.

To enable others to make and use my invention, I will proceed to describe its construction and operation.

A is the divided or slotted hook, of cast or wrought iron, made with a long stem, *a*, to be bolted to the stem or stern of the boat, either inside or outside, and having its head slotted centrally, as shown at *b b*, for the reception of the link B, thus forming two separate divisions, *c c*, of the hook, one on each side of the slot *b b*. The link B consists of a flat piece of cast or wrought iron of a thickness to pass easily into and out from the slot *b b*, and it is furnished at its upper end with a ring, *d*, or its equivalent by which to attach it to the tackle, and near its lower end with two opposite projecting pins, *e e*, to enter into the two divisions *c c* of the hook. The hook is strengthened by means of cheeks *ff*, which connect its sides with the shank *a*. The mouth of the hook is

sloped out, as shown at *g* in Fig. 2, to allow the pins *e e* to pass out easily and with a slight downward movement.

The boat is to have one of the hooks A secured to each end, as shown in Fig. 3, the mouth of both hooks having a forward direction. The two links—one for each hook—are to be suspended from the davits by separate tackles C C, as represented in Fig. 3, which should be let out from the same windlass or other lowering apparatus in such manner that both tackles will run out alike and keep the boat on an even keel during the lowering operation, as shown in red outline in Fig. 3.

When in lowering the boat from a vessel in motion it comes to a bearing on the water, the progress of the vessel instantly draws the tackles in a slanting direction, and as soon as the tackles become slack enough to permit the pins *e e* of the links B B to clear the points or extremities of the hooks the links will be at once carried forward free of the hooks by the tackles swinging toward a vertical position under the influence of gravitation. Fig. 3 shows in black outline the boat as having been just liberated, and the tackles as being about to swing forward toward a vertical position.

This device is very infallible in its operation, and its extreme simplicity renders it impossible for it to get out of order.

Having thus described my invention, I claim and desire to secure by Letters Patent as an improved article of manufacture—

A self-relieving boat-tackle device composed of a slotted hook, A, having cheeks *f*, and a flat link, B, provided with a transverse pin, *e*, the several parts being constructed and operating in the manner herein shown and described.

HENRY G. GUYON.
